The ornamental design for a microphone, as shown and described.

DESCRIPTION

FIG. 1 is a top front perspective view of a microphone showing the new design;

FIG. 2 is top rear perspective view thereof;

FIG. 3 is a front view thereof;

FIG. 4 is a rear view thereof;

FIG. 5 is a right side view thereof;

FIG. 6 is a left side view thereof; and,

FIG. 7 is a top view thereof.

The broken lines shown in the drawings illustrate portions of the microphone that form no part of the claimed design.
